OF LATERNEN-VERTRIEBS-GESELLSCHAFT MIT BESCHRÄNKTER HAFTUNG, OF
COLOGNE, GERMANY.

CYCLE-LAMP.

1,222,836.

Specification of Letters Patent.

Patented Apr. 17, 1917.

Application filed January 24, 1916. Serial No. 74,014.

To all whom it may concern:

Be it known that I, FRIEDERICK WINDHAUSEN, engineer, a subject of the King of Prussia, and a resident of Dusseldorf, Germany, have invented certain new and useful Improvements in Cycle-Lamps, of which the following is a specification.

The present invention relates to an improved acetylene-lamp, especially destined for cycles, and has for its purpose to provide a lamp of simple, compendious and durable construction.

The hitherto known lamps for cycles have many disadvantages, mainly because they are composed of a great number of separate parts soldered or riveted together, which due to the repeated shocks to which the lamps are subjected in driving, commonly after some time loosen and then are lost or have need of great repairing work for being again fastened. Further the lamps on sale are quickly going to ruin on account of their light, thin and feeble structure, and therefore become useless in a short time. The reason for this is that the single parts of the lamps are made of thin brass or iron-sheet which is naturally not able to resist great forces and wearing, thereby causing an untightness of the water-tank and many other defects of the lamps.

All these disadvantages are avoided by the present invention, the lamp forming in its main parts a single solid body of cast-metal. The lamp, therefore, consists in a single piece; the main parts, namely the carbide-box, water-tank, reflector, chimney and the gas-supply to the burner. Furthermore the new lamp, by suitably choosing the metal for its construction—mainly aluminum and copper—is so stable, that it will withstand the greatest shocks.

The invention is illustrated by the accompanying drawing in a form of construction given as example and showing a cycle lamp in longitudinal section.

The cast body *a* comprises mainly three chambers or hollow parts, viz.: a chamber *a*¹ below serving as carbide-receptacle, an upper chamber *a*² serving as water tank, and a lateral chamber *a*³ forming the reflector. At said body *a* the parts and means for working of the lamp are arranged partly detachable at the interior, partly on the outside easily accessible.

55 The carbide-chamber *a*¹ is closed at its base

by a bottom-plate *b* screwed on and thus detachable. In the interior, a receptacle *c* is supported, and in the said receptacle a hollow body *d* having several holes *e* in its wall, is also supported. The upper part of the body *d* above the carbide is surrounded by a flat ring or plate *f* upon which is mounted a spring *g* which presses upon the plate and thereby holds down the carbide and prevents it from being weakened while in use. Above the body *d* is a screw *h* which will be described more clearly hereinafter. On said screw is arranged a wing-nut *h*¹ which holds a disk *i* and a felt plate *j* against the cross-wall *k* which divides the chamber *a*¹ from the chamber *a*². In the disk *i* and the plate *f* are small openings for the passage of the acetylene-gases, which are purified by the felt.

The water which is contained in the upper chamber *a*², drops through a groove *l* along the lower part of the closing pin *m* down into the hollow body *d* and penetrates through its openings *e* into the carbide receptacle *c*. The pin *m* is at its top end provided with a handle *n* and passes through a central opening in a nut *o* which is screwed into the cover wall of the water-chamber *a*² and is of such a diameter, that when it is unscrewed, the bottom screw *h* will move through the corresponding opening in the cover-wall of the water-chamber *a*². A stopper *p* screwed in said wall serves for filling purposes.

The screw *h* is provided with a cone-shaped head which serves as a valve for tightening the screw at its passage through the wall *k*. Furthermore said screw holds and supports the pin *m* which is screwed therein with its lower end in such a position that the groove *l* extends upwardly and into the water chamber and ends below in the central perforation of the screw *h* where a small tube *q* is inserted, projecting below and leading the water in the hollow body *d*. If the pin *m* should break by too quickly turning it, the screw *h* may be removed by means of a screw-driver or the like, from above through the central opening in the cover-wall of the chamber *a*² and then pin *m* may be replaced by another.

For suitably supplying gas to the burner *r* the channels *s* and *t* which cross each other are formed in the body *a*. The channel *s* extends from the channel *t* to the burner *r*

which is screwed into the larger top-end of the channel, and is closed by a screw *v*. The channel *t* extends from the interior of the carbid chamber *a*¹ in the plane of the felt-plate *j* to the outside and is here closed by a screw *w*. After unscrewing the screws *v* and *w* the channels *s* and *t* can be quickly and easily cleaned.

I claim as new:

- 10 A casted acetylene lamp comprising a body portion including an upper water

chamber, a reflector integral therewith, a lower carbid chamber integral with the water chamber and in communication therewith, the lower end of said carbid chamber 15 having a threaded periphery, and a threaded closure adapted to coöperate with the threaded periphery of the carbid chamber for securing the same thereto.

Signed at Cologne, Germany, this 15 day 20
of October, 1915.

FRIEDERICK WINDHAUSEN.
